UNITED STATES PATENT OFFICE.

HUGH DALEY, OF CHICAGO, ILLINOIS.

HYDROCARBON-BURNER.

1,077,260.

Specification of Letters Patent.

Patented Nov. 4, 1913.

Application filed January 18, 1913. Serial No. 742,804.

To all whom it may concern:

Be it known that I, HUGH DALEY, a citizen of the United States, and a resident of Chicago, Cook county, State of Illinois, 5 have invented certain new and useful Improvements in Hydrocarbon-Burners; and I do hereby declare that the following description of my said invention, taken in connection with the accompanying sheet of 10 drawings, forms a full, clear, and exact specification, which will enable others skilled in the art to which it appertains to make and use the same.

My invention relates to improvements in 15 hydrocarbon burners, and it consists, essentially, in the novel and peculiar combination of parts and details of construction, as hereinafter first fully set forth and described, and then pointed out in the 20 claims.

In the drawings already referred to, which serve to illustrate my said invention more fully, Figure 1 is a bottom plan of 25 one of the burners employed in my invention; Fig. 2, a longitudinal, vertical section of my improved heater, and, Fig. 3, a transverse section of the same in line O—O of Fig. 2.

Like parts are designated by corresponding 30 symbols or characters of reference in all the figures of the drawing.

The object of my invention is the production of a simple and efficient portable surface heater which may be easily propelled 35 by hand, horse power, or, by attachment to a suitable motor truck, for the particular purpose of melting snow on rural delivery postal routes, on city streets and alleys, and on sidewalks. In the first named employment, my invention can be attached to either front or rear of a suitable motor vehicle, and pushed or pulled, as the case may be, over snow clogged roads. The intense 40 heat generated by my device, which, in actual use, will cover an actual area of about 30 square feet, will almost instantaneously melt all snow within its area of operation, and the resultant water will flow into the gutters at the side of the road. In the 45 case of wide country roads, two or more of these devices may be employed to serve the entire width of the road.

In practice, these devices are started out 50 after a few inches of snow have fallen and follow the storm, returning over the same route after reaching the end of their run.

As the outfits are arranged to travel at the rate of two miles an hour, it is evident that a large territory can be covered in twenty four hours by each device. In like manner 60 my motor vehicle drawn heater may be employed to dry muddy postal routes during the wet, spring season, the water on such roads being evaporated into steam and dissipated in the surrounding atmosphere. 65 Regular trips over such roads at stated intervals, will convert the same from practically impassable thoroughfares into good lanes of traffic in a short space of time.

Large municipalities spend enormous 70 sums of money every winter for snow removal from its thoroughfares. With the employment of a series of my outfits, accompanied by a sufficient squad of swabbers behind to swab the melted snow into 75 the nearest sewer manholes, streets may be cleared at the rate of two miles per hour and the water disposed of through the sewers at a fraction of the present expense. Small machines, hand propelled, may also 80 be used for clearing snow and ice from sidewalks, and, still another application is the softening of asphalt around breaks in streets for the purpose of making repairs.

In the drawings hereinbefore mentioned, I 85 illustrate my device as constructed for hand propulsion, but I wish it understood that the same may be vehicle propelled without the modification of any essential elements.

In Fig. 1, I show a bottom plan of one of 90 a series of hydro-carbon burners A, in which 1 is the hydro-carbon fluid inlet, which inlet comprises a cross 2, or the like, the side branches 3 and 3^a of which communicate with T's 4 and 4^a by means of close nipples 95 5 and 5^a. The T's 4 and 4^a in turn, connect with elbows 6 and 6^a through similar nipples 7 and 7^a. The side openings of said cross, T's, and elbows point in the same direction; i. e., toward the rear of the 100 heater, all of which construction is located transversely at the front end of the heater. From the T's 4 and 4^a and elbows 6 and 6^a, lead longitudinal, horizontal flame tubes 8, 9, 10, and 11, all of which are closed at 105 their free ends by suitable caps 8^a, 9^a, 10^a, and 11^a, which caps are maintained in fixed relationship by a supporting bar 12, so as to support said flame tubes and maintain them in parallelism. The walls of said 110 tubes, on their under sides thereof, are perforated by a multiplicity of minute, closely

spaced holes 13, extending the entire length of the same. Directly under these perforations are located metallic strips or so called baffle bars 15, for purposes hereinafter described.

Leading from the cross 2, above mentioned, between and parallel to flame tubes 9 and 10, is a similarly downwardly perforated flame tube 16. This tube is surrounded by a jacketing tube 16^a, made from brass or other metal of high heat conductivity, which tube is provided with perforations 17, registering with the perforations 17^a, in the flame tube 16. This tube is capped at its free end, as are the others, by a cap 18^a, which cap is similarly fastened to the supporting bar 12, already referred to.

Extending the entire length underneath the elbows 6 and 6^a, the nipples 7 and 7^a, T's 4 and 4^a, nipples 5 and 5^a, and cross 2 is a metallic, more or less, U-shaped cup 18, which is adapted to contain a quantity of liquid hydro-carbon, which when ignited will cause volatilization, by transmitted heat, of a mixture of hydro-carbon liquid and oxygen introduced into the said parts through the inlet member opening 1 of the cross 2, and passing through them into their respective flame tubes 8, 9, 10, and 11. If the mixture is not thoroughly volatilized when it enters these tubes, the liquid portion thereof will drip through the openings 13 onto the upper surfaces of the baffle bars 15, where said liquid will be ignited by the flame issuing from cup 18. The flames upon all of these bars 15 will, in a very few seconds, heat the pipes 8, 9, 10, and 11 until complete volatilization is attained, after which flames of intense heat value will issue from all of the openings 13. These flames being projected downwardly are split apart, as it were, by the baffle bars 15 and caused to spread on either side thereof, so that the flames from one of the flame tubes will impinge upon the flames from tubes adjacent thereto on both sides, so that the area beneath the burner A is completely covered by a flame of intense heat value. The jacket 16^a, surrounding flame tube 16, serves the same purpose as the baffle plates 15, but accomplishes the result much more rapidly. The unvolatilized liquid dropping through perforations 17 and 17^a, ignites at the periphery of the jacket and the resultant flame completely surrounds the same, thereby more quickly heating the interior tube 16 in an obvious manner. The object in more rapidly heating flame tube 16 is that the mixture entering through inlet 1, following the lines of least resistance, will more readily enter said tube, and must, therefore, be more quickly converted into volatilized matter.

A series of two or more of these burners are mounted in parallel within and near

the open bottom of a sheet metallic hood B, which is possessed of preferably converging sides 19 and 19^a, vertical front and rear ends 21 and 21^a, (the bottom edges of all of which are but a short distance above the ground level to permit the egress of the gases of combustion) and a practically flat top 20. The said rear and front ends are provided with a plurality of openings 22 and 22^a, adapted to be closed by sliding covers 23 and 23^a, so as to regulate the admission of the proper amount of oxygen to insure perfect combustion. To the end wall 21^a, at a point slightly below the inlets 1 of the burners A, are located brackets 24, supporting needle valves and bodies 25, the nozzles 26 of which are in axial alinement with said inlets 1. From these needle valve bodies lead upwardly converging hydro-carbon fluid supply pipes 27 and 27^a, which terminate in a Y-shaped casting 28, from which extends a main supply pipe 29, entering a fuel tank 29^a, located on the top of the hood B. A stop valve 30 is introduced in the fuel line 29 for evident reasons. The hood B may be mounted upon wheels C and C^a, revolving upon axles and axle brackets 31 and 31^a, in which case a stiffening member 32 is fastened on the interior of the hood to render the sides 19 and 19^a more rigid. In the fuel tank 29^a is located an air pump 33 to create sufficient pressure, within said tank, to force the liquid fuel through the nozzle 26 of the needle valve and body 25 into the inlet 1 of the burner or burners A in a state of semi-atomization.

For the purpose of propelling the complete device by hand, by horse power, or by attachment to a suitable motor vehicle, as hereinbefore described, are provided handles, shafts, or attachments 34. Any form of attachment to a propelling truck may be employed.

Having fully described my invention, I claim as new and desire to secure to myself by Letters Patent of the United States:

1. A hydrocarbon burner for the purpose described comprising an inlet member having a nozzle, a control valve, and a source of fuel supply, a plurality of downwardly perforated flame tubes connected to said inlet member, and baffle bars located under said flame tubes, beneath said perforations.

2. A hydrocarbon burner for the purpose described comprising an inlet member having a nozzle, a control valve, and a source of fuel supply, a plurality of parallel, downwardly perforated flame tubes connected to said inlet member, and a baffle bar located under each of said flame tubes, directly beneath said perforations.

3. A hydrocarbon burner for the purpose described comprising an inlet member having a nozzle, a control valve, and a source of fuel supply, a plurality of parallel, down-

- wardly perforated flame tubes connected to said inlet member, a baffle bar located under each of said flame tubes, directly beneath said perforations, a medially located, downwardly perforated flame tube also connected to said inlet member, and a downwardly perforated jacket surrounding said last named flame tube.
4. A hydrocarbon burner for the purpose described comprising an inlet member having a nozzle, a control valve, and a source of fuel supply, a volatilizing cup under said inlet member extending the entire length thereof, downwardly perforated flame tubes extending from said inlet member, and means connected to said tubes and located beneath said perforations to assist in the volatilization of fuel passing through said tubes.
5. A hydrocarbon burner for the purpose described comprising an inlet member having a nozzle, a control valve, and a source of fuel supply, a volatilizing cup under said inlet member, downwardly perforated flame tubes extending from said inlet member, means connected to said tubes and located beneath said perforations to assist in the volatilization of fuel passing through said tubes, a medially located, downwardly perforated flame tube also connected to said inlet member, and a downwardly perforated jacket surrounding said last named flame tube.
6. A hydrocarbon burner for the purpose described comprising an inlet member hav-
- ing a nozzle, a control valve, and a source of fuel supply, a volatilizing cup under said inlet member, a plurality of downwardly perforated flame tubes extending from said inlet member, and a baffle bar located under each of said flame tubes, directly beneath said perforations.
7. A hydrocarbon burner for the purpose described comprising an inlet member having a nozzle, a control valve, and a source of fuel supply, a volatilizing cup under said inlet member, a plurality of downwardly perforated flame tubes extending from said inlet member, a baffle bar located under each of said flame tubes, directly beneath said perforations, a medially located downwardly perforated flame tube also connected to said inlet member, and a downwardly perforated jacket surrounding said last named flame tube.
8. A hydrocarbon burner for the purpose described comprising an inlet member having a nozzle, a control valve, and a source of fuel supply, a downwardly perforated flame tube extending from said inlet member, and a downwardly perforated jacket surrounding said flame tube to assist in the volatilization of fuel passing through said flame tube.

In testimony whereof, I have hereunto set my hand in the presence of two subscribing witnesses.

HUGH DALEY.
